UNITED STATES PATENT OFFICE.

CHARLES E. SHAPPAT, OF ELDORADO, KANSAS.

CLAMP.

1,359,539.

Specification of Letters Patent. Patented Nov. 23, 1920.

Application filed December 15, 1919. Serial No. 344,896.

To all whom it may concern:

Be it known that I, CHARLES E. SHAPPAT, a citizen of the United States, residing at Eldorado, in the county of Butler and State 5 of Kansas, have invented a new and useful Clamp, of which the following is a specification.

This invention relates to oil well drilling apparatus, and particularly to an improved 10 device or clamp for holding clamps of an oil well temper screw from turning and twisting while drilling with a wire line cable, thereby preventing the line from wearing or spraying out and breaking immediately 15 back of the clamps of the temper screw, owing to the continual twisting of the line or wire cable during the drilling operation and while the clamps are being held, thus preventing the strands of the cable from 20 working loose and necessitating repair or renewal of the cable.

A further object of the invention is to provide an improved clamp for the purposes 25 stated, which will serve to prevent the cable from twisting and turning at such a rapid pace as to make it unsafe for the driller to operate the screw, in addition to preventing the strands of the cable from splaying out and breaking as heretofore stated, while also 30 providing a device which can be lengthened or shortened to fit screws of different lengths, or to permit movement or pulling of the cable, running of a string of casing and pulling of the same, with facility and 35 in a manner to prevent the joints of the casing from catching on the device.

With the above and other objects in view which will appear as the description proceeds, the invention resides in the combination 40 and arrangement of parts and in the details of construction hereinafter described and claimed, it being understood that, within the scope of what is claimed, changes in the precise embodiment of the invention 45 shown can be made without departing from the spirit of the invention.

In the accompanying drawings:

Figure 1 is a side elevation of the device applied to a drilling apparatus or well temper screw associated therewith; and 50

Fig. 2 is a perspective view of the clamp disassembled.

Referring to the drawings in detail, in which like reference characters designate 55 corresponding parts throughout the several views, the numeral 10 designates an oil well

drilling apparatus, including a cable 11 which is operated in the usual way, being supported by clamps 12 and 13 from the temper screw 14, the cable being effectively 60 clamped against movement as it is reciprocated vertically. The temper screw clamps are provided with handles 15 and 16, preferably in the form of cross bars, by means of which the screw may be operated to feed the 65 cable forwardly, as the drill is lifted and to turn the drill to cause the same to effectively penetrate the earth, in the drilling of the well. Ordinarily, the clamps, owing to the 70 turning of the temper screw by the continual operation of the drilling apparatus, will cause the twisting of the cable, and thereby result in the wearing and breaking of the same owing to the splaying of the 75 strands thereof, back of the clamps where the slack is carried back so that the cable 80 may be operated during the drilling operation.

To avoid the above objections, I provide my improved clamp which consists of a bar 80 17, preferably of steel of suitable width and thickness, the upper end of which is bent at right angles as shown at 18 and provided with an opening 19 therethrough. The opposite end of the bar is provided with a 85 series of spaced openings 20.

Coöperating with the bar 17 is a short bar 21 provided with a pair of openings 22 designed to coöperate with the openings 20, so as to receive clamping bolts 23, whereby 90 the bars can be fastened together rigidly and also permitted to be adjusted one relative to the other, to vary the length of the device. The lower end of the bar 21 is provided with a return bend or loop 24, the same 95 being extended horizontally in an opposite direction to the direction of extent of the end 18 at the upper end of the bar 17 and then returned therebeneath, to provide an open loop, terminating in an upwardly off-set horizontal jaw portion 25 coöperating 100 with the end portion or jaw 18 and disposed in alignment and parallel with a central enlarged bearing opening 26 and at equi-distant points at either side thereof with openings 105 27, the innermost opening being located immediately forward of the bars proper, constituting the connecting portion of the clamp, and the other opening being located near the outer end of the arm 25. The portion 25 is longer than the end portion 18 for a purpose to be hereinafter made apparent.

In the application and use of the device, the same is attached to the oil well temper screw, the bar or short section 21 serving as a plate on which the swivel of the temper screw is bolted, at the openings 27, the temper screw passing through the opening 26 and through the opening 19. By this means, the swivel will be maintained in a steady position and as the clamp hangs on the swivel, 10 the clamp will run steady without twisting thereby preventing the cable from splaying out where it is bent, and subsequently breaking. Also, by reason of the two part construction, the length of the device can be 15 regulated so as to fit temper screws of different lengths, thereby accommodating the device to well drilling apparatus of different sizes and constructions. Furthermore, the device can be unbolted so as to disconnect 20 the sections thereof whereby the loop at the bottom can be turned to the opposite side while running a string of casing thus preventing the clamp from being in the way or catching in the joints as the casing is being 25 run. Also, the device permits the raising of the swivel to remove a broken ball bearing, and renewal of said ball bearing or bearings where the swivel of the screw rests on its bearing in the usual way. This can be ac- 30 complished by removing the two bolts 23 thus leaving the swivel free, and permitting it to be easily raised while the change is being made. Also, the loop 24 is made suffi- 35 ciently large where the cross bar or handle of the clamp of the temper screw passes therethrough, that the driller can reach his

hand through the loop and turn the cross bar without clamping or pinching his hand.

Having thus described the invention what I claim is:

The combination with an oil well temper screw, a swivel connected thereto, and a clamp suspended from the swivel, of a cross bar for operating the temper screw, a bar having one end portion extending at right angles therefrom and provided with an aperture, there being a longitudinal series of apertures in the other end portion of the bar, the temper screw being extended through the first mentioned opening, a relatively short bar having a longitudinal series of openings in one end portion thereof, fastening means extending through openings of the series in the two bars for binding said bars together, said bars being adjustable relative to each other, a laterally extending return bend or loop upon the lower portion of the short bar, a jaw portion extending from said loop and having an intermediate opening through which the temper screw extends and supplemental openings, means ex- 60 tends through the supplemental openings for attaching said jaw to the swivel, said bar of the temper screw working within the loop and spaced therefrom.

In testimony that I claim the foregoing as my own, I have hereto affixed my signature in the presence of two witnesses.

CHARLES E. SHAPPAT.
